UNITED STATES PATENT OFFICE.

JOHN STOCKTON BLANKINSHIP, OF LYNCHBURG, VIRGINIA.

DESIGN FOR A COMBINED SETTEE AND PHONOGRAPH-CABINET.

53,431.

Specification for Design.

Patented June 17, 1919.

Application filed February 21, 1919. Serial No. 278,546. Term of patent 14 years.

To all whom it may concern:

Be it known that I, JOHN STOCKTON BLANKINSHIP, a citizen of the United States, residing at Lynchburg, in the county of Campbell and State of Virginia, have invented a new, original, and ornamental Design for a Combined Settee and Phonograph-Cabinet, of which the following is a specification, reference being had to the accompanying drawing, forming a part thereof.

Figure 1 is a front elevation, of a combined settee and phonograph cabinet, showing my new design.

Fig. 2 is a plan view thereof.

What is claimed is:

The ornamental design for a combined settee and phonograph cabinet, as shown.

JOHN STOCKTON BLANKINSHIP.
